UNITED STATES PATENT OFFICE.

WILLIAM C. MARTINEAU AND CLARENCE R. MARTINEAU, OF ALBANY, AND A. BENJAMIN APPLER, OF WATERVLIET, NEW YORK; SAID CLARENCE R. MARTINEAU AND SAID A. BENJAMIN APPLER ASSIGNORS TO SAID WILLIAM C. MARTINEAU.

LOCK.

1,111,599.

Specification of Letters Patent. Patented Sept. 22, 1914.

Application filed May 15, 1914. Serial No. 838,745.

To all whom it may concern:

Be it known that we, WILLIAM C. MARTINEAU, CLARENCE R. MARTINEAU, and A. BENJAMIN APPLER, each a citizen of the 5 United States of America, the said WILLIAM C. MARTINEAU and CLARENCE R. MARTINEAU each residing in the city of Albany, county of Albany, and State of New York, and the said A. BENJAMIN APPLER residing at the 10 city of Watervliet, county of Albany, and State of New York, have invented certain new and useful Improvements in Locks, of which the following is a specification.

Our invention relates to locks, and the object of our invention is to provide a lock especially adapted for use on sliding doors on a railway train, provided with a means for keeping the hasp on the staple; together with such elements and combinations as are 20 hereinafter more particularly set forth and claimed. We accomplish these objects by means of the mechanism illustrated in the accompanying drawing, in which:

Figure 1 is a perspective view of our lock 25 in a closed position. Fig. 2 is a perspective view showing the hasp off of the staple. Fig. 3 is a reverse plan view of the hasp, showing its connection with the hasp plate. Fig. 4 is an enlarged plan view of the end of 30 the hasp plate, with parts broken away, showing the place where the insertion of the hasp is made. Fig. 5 is a detail view of the curved end of the hasp. Fig. 6 is a section along the lines, 1—1, on Fig. 4. Fig. 7 is a detail view showing the end of the hasp inserted through the opening in the end of the hasp plate and retained so as to be drawn 35 into its hinging position therein.

Similar letters refer to similar parts 40 throughout the several views.

The hasp, A, is provided with a series of openings, B, B, either one of which is adapted to fit upon the staple, C, depending upon whether the door is closed tightly or not. 45 The hasp is provided with a curved shank, D, and rounded head, E, at the end thereof. The hasp plate, F, is provided at one end with a cup-shaped portion, H, into which the rounded head, E, of the hasp may be 50 placed and rotate when the hasp is placed on and taken off of the staple, C. In the cup-shaped portion, H, there is an elongated slot, G, which will permit of the hasp, A, being inserted therethrough, all except the

rounded head, E, thereon. As thus arranged, the hasp may be moved outward off of the staple and downward to assume a vertical position held by the rounded head of the hasp in the hasp plate.

Above the staple we pivot two buttons, J 60 and K, each provided with a arm, L, M, adapted to rest against the opposite sides of the staple, C, as shown in Fig. 1, and when the hasp is in the position shown in said Fig. 1, the buttons, J and K, resting against the opposite sides of the staple, it is apparent that the hasp is held onto the staple by the buttons. Any vibration or motion of the car, providing these are used on a car door, will tend to throw one of the buttons 70 away from the staple and cause the other of said buttons to be kept close in contact with the staple. At the end of each of the buttons, J and K, we place the fingers, O and P, which when pressed toward each other 75 will rotate the buttons, causing them to assume the position shown in Fig. 2, permitting of the removal of the hasp from the staple. A stop pin, R, is placed between and at the upper portion of the buttons, J 80 and K, against which the fingers, O and P, will engage and prevent further opening of the buttons, as shown in Fig. 2.

Through the arm, L, M, which may be placed in contact with the staple, we place 85 an opening, T, registering with the opening, t, in the staple, through which openings, T and t, any locking member such as a wire, U, as shown in Fig. 1, may be placed.

We have shown the staple, C, and the buttons, J and K, and stop, R, mounted upon a plate, V, the plate having a right-angled projecting portion, v, bolted to the door jamb, X. But we do not limit ourselves to this manner of attaching the staple or its 90 connections.

The sliding door, Z, carries the hasp plate, F, but it is apparent that it is not necessarily a sliding door on which our locking attachment is placed, and we do not wish to 100 limit ourselves to any particular place, nor to the exact construction of our invention.

What we claim as our invention and desire to secure by Letters Patent is:

1. The combination of a hasp; means for hinging the same; a staple adapted to be placed through the opening in the hasp; two buttons pivoted above and adjacent to

- each side of the staple, arranged to hang by gravity over the hasp and against the opposite sides of the staple, substantially as described.
- 5 2. The combination of a hasp; a hasp plate provided with cup-shaped portion and an elongated slot therethrough; a curved portion on said hasp so arranged that the hasp may be inserted through said elongated 10 slot with the exception of said rounded end portion which is adapted to articulate in said cup-shaped portion; a staple upon which the hasp may be placed by causing the staple to project through the opening in 15 the hasp; means on each side of the staple for engaging the hasp after it has been placed in position on the staple, preventing the accidental withdrawal of the hasp from the staple, substantially as described.
3. The combination of a hasp; means for 20 hinging the same; a staple adapted to pass through an opening in the hasp; depending buttons adapted to pass over the hasp and lie on opposite sides of the staple; an oblique projecting finger at the upper end of 25 each button; with a stop pin placed between the upper portions of the buttons with which said fingers will engage and stop the upward rotary movement of each button.

In testimony whereof we have affixed our 30 signatures in presence of two witnesses.

WILLIAM C. MARTINEAU.
CLARENCE R. MARTINEAU.
A. BENJAMIN APPLER.
